SHIELD

Filed March 28, 1928

UNITED STATES PATENT OFFICE

MARGARET DONOVAN, OF TULSA, OKLAHOMA, ASSIGNOR OF ONE-HALF TO EDWARD A. WYCOFF, OF TULSA, OKLAHOMA

SHIELD

Application filed March 28, 1928. Serial No. 265,462.

The present invention relates to shields preferably constructed of asbestos or other suitable material of a like nature and has for its prime object to provide a device of this 5 nature which may be used in beauty parlors for customers to wear during marcelling or hair drying etc., so as to be protected from the mechanical instruments used thereby preventing the ears, neck, cheeks, and the like 10 from becoming burnt, scarred, or otherwise detrimentally affected.

A further important object of the invention resides in the provision of a shield of this nature which is simple in its construction, strong 15 and durable, inexpensive to manufacture, and thoroughly efficient and reliable for the purpose intended.

With the above and numerous other objects in view, the invention resides in certain novel 20 features of construction as will be hereinafter more fully described and claimed.

In the drawings:

Figure 1 is a perspective view of the shield showing the same in use,

25 Figure 2 is a perspective view of the shield looking at the rear,

Figure 3 is a plan view of the shoulder cape portions, and

30 Figure 4 is a fragmentary plan view of the collar portion.

Referring to the drawings in detail, it will be seen that the numeral 5 denotes a shoulder cape which is formed with an inner arcuate edge 6 and an outer edge the intermediate portion 35 of which is of an elongated arcuate formation as indicated at 7 while the ends are more pronouncedly arcuate as indicated at 8. The numeral 9 denotes the collar portion which has an arcuate edge 10 sewed to the 40 arcuate edge 6 and being of equal length thereof. The collar is cut away at the back as at 11 and the sides thereof are sufficiently wide so as to provide wing portions adapted to cover the ears and the major portions of the 45 cheeks of the wearer.

Both the collar and the cape portions are constructed preferably of asbestos or other equivalent material having sufficient stiffness so that the collar will stand up as illustrated 50 in Figure 1 under the hair of the beauty par-

lor patron. A suitable fastening device 12 is provided for holding the shield properly in place. The shield serves as a protection to the customer when heat or other mechanical methods are being used for the treatment of 55 the heads, and also serves as a protection to the clothes during the treatment.

The collar portion 9 is divided into two parts as is indicated at 15 in order that the shield may be more easily folded and more 60 easily fitted to the person. The slit 15 also affords means for accommodating the shield to different sized heads.

It is thought that the construction, utility 65 and advantages of this invention will be now quite apparent to those skilled in this art. It is apparent that changes may be made within the scope of the invention as hereinafter claimed.

Having thus described my invention, what 70 I claim as new is:

1. A shield of the class described including a shoulder cape and a collar fixed thereto, both constructed of relatively stiff material 75 said collar being provided with a pair of upstanding wings for engagement against opposite sides of the wearer's face for protecting the ears and cheeks.

2. A shield of the class described comprising a shoulder cape and a collar fixed thereto, both being constructed of relatively stiff material and of non-inflammable material, said collar being provided with a pair of upstanding wings for engagement against opposite sides of the wearer's face, to protect the ears 85 and cheeks thereof.

In testimony whereof I affix my signature.

MARGARET DONOVAN.
